[57] CLAIM

The ornamental design for a buffet, as shown and de-
scribed.

DESCRIPTION

FIG. 1 is a front perspective view of the buffet showing
my new design;

FIG. 2 is a top plan view thereof;

FIG. 3 is a front elevational view thereof;

FIG. 4 is a side elevational view, the opposite side being
a mirror image thereof; and

FIG. 5 is a rear elevational view thereof.
